Primary Examiner — Catherine A Tuttle(74) *Attorney, Agent, or Firm* — Sterne, Kessler,
Goldstein & Fox P.L.L.C.**CLAIM**The ornamental design for a toy musical instrument, as
shown and described.**DESCRIPTION**

FIG. 1 is a top front perspective view of the toy musical instrument showing my new design; and,
 FIG. 2 is another top and front perspective view thereof.
 The broken lines depict elements of the toy musical instrument that form no part of the claimed design.

1 Claim, 1 Drawing Sheet(56)
